UNITED STATES PATENT OFFICE.

EMILE F. WEIDIG, OF NEW ORLEANS, LOUISIANA.

LANTERN.

SPECIFICATION forming part of Letters Patent No. 729,463, dated May 26, 1903.

Application filed December 31, 1902. Serial No. 137,318. (No model.)

To all whom it may concern:

Be it known that I, EMILE F. WEIDIG, a citizen of the United States, and a resident of New Orleans, in the parish of Orleans and State of Louisiana, have invented a new and Improved Lantern, of which the following is a full, clear, and exact description.

The invention relates to oil-lanterns of the tubular type; and its object is to provide a new and improved lantern which is simple and durable in construction, cheap to manufacture, and arranged to securely hold the chimney in place by wires secured to the base and engaging the crimped top of the chimney.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a perspective view of the improvement. Fig. 2 is a plan view of the same, showing the bail swung to one side to allow removal of the chimney for filling the font or lighting the lamp. Fig. 3 is a sectional side elevation of the improvement, and Fig. 4 is a plan view of the base.

The base A of the lantern is in the form of a disk having a depending annular flange A', and on the top of the said base is soldered or otherwise secured the bottom of a font B for containing the oil and supporting a burner C and a wick-regulator D, employed for adjusting the wick E in the usual manner. On the base A, outside of the font B, are struck up lugs A², on which the lower edge of a chimney F is adapted to rest, so that the lower edge of the chimney forms with the top of the base between the said lugs air-spaces for the passage of air to the space between the font B and the inclosing lower end of the chimney F.

As will be readily understood by reference to Fig. 3. The top of the base A, outside the spaced lugs A², is formed with an annular raised portion A³ for strengthening the base and for forming a shield or deflector for the air-passages between the lugs. The tops of the lugs A² are about on a level with

the top of the raised portion A³, so that the air-passages are sheltered directly behind the raised portion, and hence a strong wind is prevented from passing into the air-passages and extinguishing the lamp by too much draft. By this arrangement the necessary amount of air readily passes to the inside of the chimney to the burner C to insure a proper burning of the oil on the wick.

The crimped top F' of the chimney F is adapted to be engaged and pressed downward by the upper ends G' of arched wires G, secured at their lower ends G² on the base A by the wires passing through openings in the top of the base and by having the ends G², formed in the shape of horizontal arms, abutting against the under side of the base. The upper ends G' of the wires G are pivotally connected with the ends of a bail H, having its sides crossed and inclosed in an adjusting-ring H', the upper end of the bail terminating in a coil H², adapted to be taken hold of by the operator to conveniently carry the lantern about. It is understood that by the operator pressing the sides of the bail above the ring H' the ends G' are swung apart out of engagement with the crimped top F' of the chimney F, so that the latter can be readily lifted off the base to permit filling the font B with oil and to manipulate the adjusting device D to bring the wick into the proper position. When the pressure is released on the sides of the bail H, then the latter closes, and thereby moves the upper ends G' of the wires G inward and back into engagement with the crimped top F' of the chimney F, and the latter is again placed in position on the lugs A² of the base A. Now by having the wires G arranged in the manner described downward pressure is exerted by the ends G' on the chimney-top to hold the latter securely in position on the lugs A² and around the font B, forming a permanent fixture of the base A.

In lighting the wick when the chimney F is removed, as above described, it is desirable that the flame shall extend about half the usual height, and then the chimney is replaced and locked in position, as above described. The flame now soon reaches its full height without danger of smoking and produces a powerful light. It is understood that

the flame rises to the desired extent as soon as the chimney is sufficiently heated to heat the incoming air passing to the burner.

5 The lantern described can be very cheaply manufactured and can be easily manipulated to produce a good flame at the burner.

Having thus described my invention, I claim as new and desire to secure by Letters Patent—

10 1. A lantern, comprising a base, a chimney resting on the base, upwardly-extending wires held on the base outside the chimney and bent toward each other at their upper ends and terminating in eyes, overreaching 15 and engaging the top of the chimney, pressing the same downwardly upon the base of the lantern, and a bail for the lantern, said bail being pivotally secured to said upwardly-extending wires, the eyes at the upper extremities of said wires also forming pivot-points for the bail, as specified and for the purpose set forth.

20 2. A lantern comprising a base, a font permanently secured to the base, a chimney resting on the base and surrounding the font, and forming with the latter air-spaces for the 25 passage of air to the burner, wires held on the base, outside of the chimney, and adapt-

ed to engage with their upper ends the top of the chimney, to hold the latter in position 30 on the base, a manipulating-bail, pivotally connected with the upper ends of the wires, for opening and closing the same and for carrying the lantern about, said bail being formed of spring-wire and having its lower 35 ends crossed, and a ring surrounding the two sections of the bail at their crossing-point, as set forth.

3. A lantern having a base provided on its top with spaced chimney-resting lugs, a raised 40 annular portion outside the said lugs extending up into about the same plane with the lugs, a font permanently secured to the said base within the said lugs, for the chimney to inclose the font, and wires held on the base 45 and adapted to engage the top of the chimney, to hold the latter in position on the said lugs, as set forth.

In testimony whereof I have signed my name to this specification in the presence of 50 two subscribing witnesses.

EMILE F. WEIDIG.
